GUN SIGHT

Crawford C. Loomis, Ilion, N. Y., assignor to
 Remington Arms Company, Inc., a corporation
 of Delaware

Application April 9, 1937, Serial No. 135,872

4 Claims. (Cl. 33—47)

This invention relates to gun sights, and particularly to the type of front sight in which any one of a number of readily interchangeable reticules may be inserted and properly held in a tubular supporting and shielding member.

More specifically, the invention contemplates a novel construction of reticule and means associated with the hood cooperating with the novel reticule for accurately locating and securely holding the reticule, while permitting its ready removal and replacement when desired. In appliances of this character correct sighting requires that the interchangeable reticule be accurately positioned in the hood and the periphery of the hood be closed against the admission of light. Many devices for this purpose, usually of rather complex construction, have been proposed; as well as a number of simple appliances in which no means is provided for insuring that the reticule is properly seated and therefore capable of establishing the correct sight line. The present invention contemplates the accurate seating of the reticule and the closing of the reticule slot against the admission of light by means of extraordinary simplicity and effectiveness.

In the drawing:

Fig. 1 is a side elevation of a sight including one embodiment of the invention.

Fig. 2 is an end elevation of the same sight.

Fig. 3 is an enlarged fragmentary, longitudinal, sectional elevation, the reticule retaining member being in partially retracted position.

Fig. 4 is a front view of a reticule embodying one form of the invention, removed from the hood.

The sight comprises a tubular hood 10 provided with the usual dovetailed block 11 for attachment to a gun barrel or the supporting block secured to a gun barrel. The forward end of the tubular hood is of somewhat less diameter than the rearward end, and the rearward end is interiorly threaded to receive the threaded shank of a tubular reticule holding member identified generally by the numeral 12 and provided with a manipulative head 13. At the junction of the forward and rearward sections of the hood is a semi-cylindrical transverse slot 14 adapted to receive a reticule, one form of which is shown in Fig. 4 and which is identified generally by the numeral 15. Preferably the slot 14 is somewhat wider than the reticule, to facilitate ready insertion and removal of the reticule. As illustrated in Figs. 3 and 4, the reticule consists essentially of a ring comprising a lower half 16 of an exterior diameter substantially equal to the interior

diameter of the hood 10, and an upper half 17 having an exterior diameter substantially equal to the exterior diameter of the hood 10. At the junction of the parts 16 and 17 manipulative ears 18 may be placed, the lower surface 19 of said ears resting upon the end walls of the slot 14 and temporarily locating the reticule in substantially correct position when it is first dropped into the slot 14. Projecting upwardly from the bottom of the reticule ring is a sighting element 20 of any desired configuration. It will be understood that the sight surface which has been shown in the drawing is illustrative only, and that the use of a set of interchangeable reticules comprising a number of differing sight surfaces 15 is contemplated. The reticule securing means is as follows:

Within the ring 16—17 of the reticule is formed a groove 21 which in section is preferably V-shaped although other sections may be used when special circumstances render them desirable. The threading of the shank of the reticule holding member terminates at such a point as 22, providing an unthreaded end section 23. Said tubular end section 23 terminates in a configuration corresponding to the configuration of the groove 21. As illustrated this configuration is that of a V. There is thus provided a pointed ring 24 of the same configuration and diameter as the groove 21 in the reticule. As the reticule holding member is rotated and advanced, the ring 24 engages the groove in the reticule and, due to the V configuration of both, the reticule will be drawn into and securely held in correct position. The thickened wall of the forward end of hood 10 provides adequate support for the reticule, and it is thus engaged and held by the retaining member. The forward face of the upper portion 17 of the reticule is pressed into contact with the forward margin of the slot 14 and the part 24 enters and engages the margin of the V-groove 21; thus effectively closing all portions of the reticule slot 14 against the admission of light. When a change of reticule is desired, the particular reticule which is thus held in the slot may be very readily removed by slightly retracting the retaining member and engaging the parts 18, or merely by inverting the firearm and permitting the reticule to drop out.

It will be understood that the embodiment of the invention illustrated and described is typical and representative only, the invention being susceptible to many modifications, all falling within the scope of the appended claims.

What is claimed is:

1. A reticule for a firearms sight comprising a ring having two portions of differing exterior diameters, and manipulative means associated with said ring, there being a continuous circular groove in said ring adapted for engagement by a reticule retaining member.
2. In a firearms sight, in combination, a cylindrical hood having therein a semi-cylindrical transverse slot adapted to receive and support a reticule, a reticule adapted for insertion in said slot, said reticule comprising a ring having an annular groove in one face thereof, and reticule retaining means adjustably supported in said hood comprising an annular projection adapted to enter the groove in said reticule when said reticule is in operative position within said slot, thereby positioning and retaining said reticule in said hood.

3. In a firearms sight, in combination, a cylindrical hood having therein a semi-cylindrical transverse slot adapted to receive and support a reticule, a reticule adapted for insertion in said slot, means for retaining said reticule in operating position within said slot comprising a continuous circular groove in one face of said reticule, and a tubular member threaded into said hood and having an end portion adapted to enter said groove.

4. ~~A reticule for a firearms sight comprising a ring having front and rear faces, and a sight surface supported from said ring, there being an annular groove in one face of said ring adapted for engagement by a reticule retaining member.~~ 15
